Primary Examiner — R. Johnson(74) *Attorney, Agent, or Firm* — Joseph Leone; DeWitt LLP(57) **CLAIM**

The ornamental design for a clip-on musical instrument tuner, as shown and described.

DESCRIPTION

FIG. 1 is a right side elevational of a clip-on musical instrument tuner showing my new design;

FIG. 2 is a left side elevational view thereof;

FIG. 3 is a front elevational view thereof;

FIG. 4 is a rear elevational view thereof;

FIG. 5 is a top plan view thereof; and

FIG. 6 is a bottom plan view thereof;

FIG. 7 is a rear, right perspective view thereof; and,

FIG. 8 is another, alternative left-side elevational view thereof.

The broken lines represent the portions of the clip-on musical instrument tuner that form no part of the claimed design.
